BED MOUNTED SWEEPER FOR A PICKUP TRUCK

Charles F. Reeves, 1200 S. Monaco Parkway,
Denver, Colo. 80222

Filed Oct. 1, 1973, Ser. No. 402,366

Term of patent 14 years

Int. Cl. D12—13

U.S. Cl. D49—9.1

FIG. 1 is a front perspective view of a bed mounted sweeper for a pickup truck showing my new design;

FIG. 2 is a rear elevation view thereof to a slightly enlarged scale;

FIG. 3 is a left side elevation view thereof;

FIG. 4 is a front elevation view thereof;

FIG. 5 is a top plan view thereof; and

FIG. 6 is a bottom plan view thereof.

The right side elevation view is a mirror image of the left side elevation view.

I claim:

The ornamental design for a bed mounted sweeper for a pickup truck, as shown and described.
